JAMES K. BURLEIGH AND LAUREN V. WHITE, OF KALAMAZOO, MICHIGAN, ASSIGNEES,
BY DIRECT AND MESNE ASSIGNMENTS, TO ARTHUR L. ZWISTER, OF KALAMAZOO,
MICHIGAN.

SIGNALING DEVICE FOR AUTOMOBILES.

1,213,456.

Specification of Letters Patent. Patented Jan. 23, 1917.

Application filed July 8, 1915. Serial No. 38,824.

To all whom it may concern:

Be it known that we, JAMES K. BURLEIGH and LAUREN V. WHITE, citizens of the United States, residing at Kalamazoo, in the county of Kalamazoo and State of Michigan, have invented certain new and useful Improvements in Signaling Devices for Automobiles, of which the following is a specification.

This invention relates to improvements in signaling devices for automobiles and similar vehicles.

The objects of this invention are: First, to provide an improved signaling device, to be carried by an automobile or similar vehicle for indicating the direction in which said vehicle is about to turn. Second, to provide an improved signaling device having a face plate provided with 20 play openings therein, suitable legends behind said openings, and shutters working between said openings and said legends to display and conceal the same. Third, to provide a signaling device having a face plate, a body plate carrying the working parts, a casing and improved means for assembling said parts in relation to each other.

Further objects, and objects relating to 30 economies of manufacture and details of construction will definitely appear from the detailed description to follow.

We accomplish the objects of our invention by the devices and means described in 35 the following specification.

The invention is clearly defined and pointed out in the claims.

A structure constituting a preferred embodiment of our invention is clearly illustrated in the accompanying drawings forming 40 a part of this specification, in which:

Figure I is a diagrammatic view showing a wiring scheme for our signaling device. Fig. II is a view in front elevation of our 45 signal, one of the shutters being actuated to display the "left" signal, the legends concealed by the other shutters being indicated by dotted lines. Fig. III is a view in front elevation of the body plate, the 50 face plate being removed, and the shutters and other parts being shown in the same relative positions as in Fig. II. Fig. IV is a sectional view, on a line corresponding to the irregular line 4-4 of Fig. V, showing

in detail the parts carried by the rear side 55 of the body plate, the parts being shown in the same relative positions as in Figs. II and III. Fig. V is an enlarged, vertical, sectional view, on the line 5-5 of Figs. II and IV. Fig. VI is an enlarged, fragmentary, detail, sectional view, on a line corresponding to the line 6-6 of Figs. II and IV, showing in detail the method of mounting the signal on the universal bracket so as to secure the casing and face 60 plate together. Fig. VII is an enlarged, detail, sectional view, on the line 7-7 of Figs. III and IV, showing in detail the finger on the armature lever extending beneath the shutter to actuate the same. Fig. 70 VIII is an enlarged, detail, sectional view, on the line 8-8 of Fig. IV, showing in detail the pivotal mounting of one of the armature levers. Fig. IX is a view in side elevation of the signal and bracket showing 75 the bracket in position to be attached to a vertical surface.

In the drawing, similar reference characters refer to similar parts throughout the several views, and the sectional views are 80 taken looking in the direction of the little arrows at the ends of the sectional lines.

Considering the numbered parts of the drawing, our improved signal comprises a face plate 1 having symmetrically arranged 85 openings 2 at the right and left, and an opening 3 toward the top of the face plate. Said face plate is provided with a rearwardly-directed circumferential flange 4 and a rod 5, of spring metal is disposed 90 within said flange 4 as shown in Fig. V; for the purpose which will presently be described. The plate 6 is disposed behind the face plate 1 fitting within the rearwardly-turned flange 4, as shown in Figs. IV and V. 95 Plate 6 is provided with a cut away portion 7 at the bottom thereof, for a purpose which will presently be described. The plate 6 and the face plate 1 are held in position relative to each other by means of the bolt 8 100 passing through both of them and carrying a spacing sleeve 9 which, together with the spring rod 5, holds the face plate 1 and the plate 6 in spaced relation to each other. In practice, we make the face plate white and upon the plate 6 in line with the openings 2-2, we form red back grounds 2'-2' on 105 which the respective legends "Left" and

"Right" appear in white letters. We also form a red back ground 3' in line with the opening 3 on which the legend "Stop" appears in white letters. These particular colors, legends and arrangements are not essential to our invention, but we use them because the combination of red and white is the usual danger signal, and the openings are so arranged on the face plate that the effect of a semaphore is produced whenever one of the shutters is actuated.

The triangular shaped shutters 10 have their inner ends pivotally mounted on the sleeve 9, as shown in Figs. III and V, so that these shutters can turn on said sleeve so as to move from their normal position in front of the corresponding display openings in the face plate. We contemplate any means for actuating said shutters as within the spirit of our invention, but the electromagnetic means here shown and described, we have found to be very suitable for this purpose.

Solenoids 11—11 are carried by brackets 12—12 which are attached to the plate 6 by the bolts 13—13. A bridge 14 has the ends 15, thereof, bent at an angle and secured to the brackets 12, and provided with grooves 16—16 in which the wires connected to the solenoids are clamped by the brackets. The pivot pins 21—21 are provided with the shoulders 18 and each pin is mounted with its forward end projecting through an opening in plate 6. The forward end of the pin 35 is upset and shoulder 18 rests on the rear face of plate 6. The armature levers 24 are provided with ears 25' through which the pivot pins 21 pass so that the levers are pivotally mounted on pins 21. Screws 23 40 are threaded into the ends of pins 21 so as to keep the armature lever from being displaced from said pins. The ends of the armature levers extend over the solenoids 11 and act as armatures therefor. The inner ends of the armature levers 24 are provided with laterally extending fingers 25 which extend through slots 26—26 formed in the plate 6 beneath the shoulders 10' which are formed on the shutters 10 at 50 points near the pivots thereof, so that, when either one of the armature levers is actuated, the corresponding shutter will be lifted to display the legend behind it.

The bracket 27 is secured to the plate 6 by the bolt 28 and carries the solenoid 29. The armature lever 31 is pivotally mounted on plate 6 in the same way as levers 24. The inner end of said lever acts as the armature for the solenoid 29, while the other end 60 32, thereof, engages beneath the lever 33, pivoted in the bracket 35 secured to plate 6. Guides 36—36 are secured to the front face of the plate 6 by bolts 37 and provided with forwardly directed flanges 38 and 39 respectively, the shutter 40 being guided for verti-

cal movement between the vertical flanges 38—38. Said shutter 40 is provided with a rearwardly directed finger 41, struck back from the upper edge thereof, and guided in the slot 42 formed in the plate 6. The flanges 39 act as stops to limit the upward movement of the shutters 10, as clearly appears from Fig. III. The lever 33 is provided with a curved fulcrum end 34 which extends beneath the finger 41 so that when the armature 31 is actuated, the shutter 40 will be lifted to display the legend "Stop" through the opening 3 in the face plate. These parts are inclosed by a casing 43 having a forwardly directed flange 44 which fits around the rearwardly directed flange 4 of the face plate 1 so that the parts are all inclosed in a tight casing. A curved bar 45, of spring metal, is disposed within the flange 4 of the face plate and to the rear of the plate 6. The spring tension of bar 45 causes it to press outwardly against the flange 4 to hold it taut and to keep the face plate from warping out of shape. This bar 45 also gives sufficient stock for the screws 46 which pass through the flanges 4 and 44 and into the bar 45 to fasten the casing and the face plate together. An opening 44' is provided in the bottom of the casing so that the dust and dirt which sifts into the interior of the signal will pass out through this opening. It is for this reason that the cut-away portion 7 is provided in the lower part of the plate 6 so as to allow the dust and dirt to pass from the front of the casing out through the opening 44'.

The signal is carried by a bracket 47 having upwardly extending arms 48 through the upper ends of which bolts 50 extend and screw into the bar. Spring washers 49 are interposed between the ends of the arms 48 and the casing so that by tightening the bolts 50, the signal can be held in its adjusted position relative to the bracket. In Fig. IX, we have shown in side elevation the signal and the bracket in different relative positions. In Fig. IX the bracket is so adjusted that it can be attached to a vertical surface instead of a horizontal surface, as in the other views.

In Fig. I, we have shown a diagrammatic view of a wiring scheme for our signal. According to this scheme, one wire from each of the solenoids 11 is grounded as at 51. Other lines 52—52 pass from each solenoid to a post on the switch 53. The line 54 leads from the third post of the switch 53, to one terminal of a battery, or source of current, 55, the other terminal of said battery is grounded as at 56. The switch 53 is preferably located upon the steering column, just beneath the wheel, where it is easily accessible to the driver, and it will be evident that by manipulating this switch a circuit will be closed through one or the other of the 130

solenoids 11, energizing the same, and lifting the corresponding shutter. From the solenoid 29, one line 53', leads to a contact 59 carried beneath the floor 60 of the vehicle, 5 but insulated therefrom. The floor of the vehicle carries a second contact 61 which is connected by line 62 with the battery. The contacts 59 and 61 are of spring metal and contact 59 is connected by a flexible connection 63 with the brake rod 64, so that when brake rod 64 moves forward, in applying the brakes, contacts 59 and 61 engage and the circuit will be closed through the solenoid 29, energizing the same, so as to lift the shutter 40 to display the legend "Stop".

In the construction, which we have here illustrated and described, we show one means for automatically energizing the solenoid 29 when the brakes are applied. This particular arrangement is not essential to our invention. We contemplate the use of any means for closing the circuit through the solenoid 29, as within the spirit of our invention.

From the description of our invention given above, the operation of the device should be very readily understood. We have already stated that the switch 53 is preferably located upon the steering column beneath the wheel. By turning the switch lever to the left, the circuit will be closed through the solenoid 11, which actuates the left hand shutter, and similarly by turning a switch lever to the right, the solenoid 11, 30 which actuates the right hand shutter, will be energized. When the switch lever is between these two positions, both of the shutters will remain in their normal positions, behind the display openings 2, concealing the legends 35 behind them. As both of the solenoids 11 operate in exactly the same way to actuate the shutter, we will describe the operation of but one of these. When the solenoid 11 is energized, it attracts the outer end of the 40 armature lever 24, as shown in Fig. IV. This armature lever 24, being mounted on the pivot pin 21, is caused to rock thereon. The inner end of the lever is provided with the finger 25 working in the slot 26 and said 45 finger engages beneath the shoulder 10' of the shutter 10, as shown in Fig. III, so that the rocking of the armature lever upon its pivot, caused by the energizing of the solenoid 11, lifts the shutter 10 so as to display 50 the legend upon the plate 6 through the corresponding display opening 2 in the face plate. The finger 25 in its normal position 55 engages the lower end of the slot 26, and since the shoulder 10' of the shutter 10 rests 60 on said finger 25, this serves to limit the movement of the shutter in one direction. The upward movement of the shutter 10 is 65 limited by the inclined flange 39. The wires leading to the solenoids 11 and 29 are carried by a cable 62' which is brought into the

bridge 14, and the wires leading to the solenoids 11 are clamped in the grooves 16, between the brackets 12 and the ends 15 of bridge 14. This holds the wires securely and prevents them from coming loose through the jar and vibration. The wire leading to the solenoid 29 is similarly clamped in place.

As we have already explained, the solenoid 29 is connected so that when the brakes 75 are applied, the circuit will be closed through the solenoid 29, and the latter will be energized. The end of the armature lever 31 is attracted toward the solenoid, and the end 32 of the armature lever moves upwardly. This end engages beneath the lever 33 which is pivoted to the plate 6, and the curved fulcrum end 34 thereof, engages beneath the finger 41 of the shutter 40, so that the movement of the armature lever 31 80 lifts the shutter 40 vertically between the guide flanges 38 so as to display the legend "Stop" through the display opening 3.

The rearwardly-directed circumferential flange 4 of the face plate 1 fits snugly within the forwardly-directed circumferential flange 44 of the casing 43, so that the two together make a tight casing within which the working parts of the signal are contained. The plate 6 which carries the working parts is connected to the face plate by the bolt 8, and the plate 6 is held spaced from the face plate by means of the sleeve 9, and the spring rod 5, the plate 6 being held so spaced from the face plate that there is plenty of room for the shutters 10-10 which are pivoted upon sleeve 9 to work easily between the face plate 1 and the plate 6.

We have already explained the manner in which the signal is mounted upon the bracket 47 so that the bracket can be mounted upon a surface at any angle, and the signal will be kept with its face plate vertical. In practice, the signal is usually applied to a vehicle by fastening to the left hand rear fender, but this location is not essential and we contemplate making these signals so that they can be attached to the cap of the radiator, or in any other position upon the 110 automobile.

We are aware that the particular embodiment of our invention, which we have here shown and described, is susceptible of considerable variation without departing from the spirit of our invention, and therefore, we do not wish to be restricted to the specific structure here shown, except as required by the appended claims. We have found, however, that this particular structure is very 125 desirable from many standpoints, and therefore, we desire to claim the same specifically, as well as, broadly, as indicated by the appended claims.

Having thus described our invention, what 130

we claim as new, and desire to secure by Letters-Patent to be is:

1. In a device of the class described, the combination of a face plate, provided with display openings therein, a plate disposed parallel to said face plate and connected thereto, said plate being provided with legends in line with said display openings, a pair of shutters pivoted and movable between the corresponding legends and certain of said display openings, guides secured to the front of said plate and disposed to limit the upward movement of said shutters, a third shutter vertically movable between said guides and provided with a rearwardly directed finger, said plate being provided with a slot through which said finger extends, said third shutter being movable between one of said display openings and the corresponding legend, electromagnets carried by the plate bearing said legends, an armature lever for each electromagnet pivotally mounted on said plate, fingers extending laterally from two of said armature levers, said plate being provided with slots through which said fingers extend beneath the lower edges of the corresponding shutters, a lever pivotally mounted on said plate, and having the end thereof engaging beneath the rearwardly directed finger of the third shutter, the third armature lever being disposed with the end thereof engaging beneath said lever to actuate the same, and a casing, all co-acting substantially as described, and for the purpose specified.
2. In a device of the class described, the combination of a face plate, provided with display openings therein, a plate disposed parallel to said face plate and connected thereto, said plate being provided with legends in line with said display openings, a pair of shutters pivoted and movable between the corresponding legends and certain of said display openings, guides secured to the front face of said plate and disposed to limit the upward movement of said shutters, a third shutter vertically movable between said guides and provided with a rearwardly directed finger, said plate being provided with a slot through which said finger extends, said third shutter being movable between one of said display openings and the corresponding legend, electromagnetic means for actuating said shutters and a casing, all co-acting substantially as described, and for the purpose specified.
3. In a device of the class described, the combination of a face plate provided with a pair of direction-indicating legends disposed in line with said display openings, a bolt connecting said face plate and said plate, a pair of shutters pivoted on said bolt,

and movable between said legends and said display openings, said plate being provided with slots, electromagnets mounted on the rear of said plate, armature levers for each of said magnets pivoted on the rear of said plate, and provided with laterally directed fingers extending through said slots beneath the lower edges of said shutters, whereby said shutters will be lifted when said magnets are energized.

4. In a device of the class described, the combination of a face plate provided with a rearwardly directed peripheral flange, and provided with display openings, a plate carrying shutters movable behind said display openings, shutter actuating means carried by said plate, a spring metal bar disposed within said flange at the rear of said plate and extending around the periphery thereof, a casing provided with a forwardly directed peripheral flange fitting around the rearwardly directed flange of said face plate, fastening means passing through said flanges, and into said bar, a bracket provided with a pair of upwardly extending arms, and bolts passing through the ends of said arms and into said flanges and bar.

5. In a device of the class described, the combination of a face plate provided with a rearwardly directed peripheral flange, and provided with display openings, a plate carrying shutters movable behind said display openings, shutter actuating means carried by said plate, a casing provided with a forwardly directed peripheral flange fitting around the rearwardly directed flange of said face plate, fastening means passing through said flanges, a bracket provided with a pair of upwardly extending arms, and bolts passing through the ends of said arms and into said flanges.

6. In a device of the class described, the combination of a face plate provided with display openings, a plate provided with legends in line with said display openings, and having a cut away portion at the bottom thereof, and a casing inclosing said parts, and provided with a vent adjacent the cut away portion of said face plate.

7. In a device of the class described, the combination of a casing, a face plate having a display opening therein, a plate bearing a legend in line with said display opening, a pivoted shutter movable in front of said legend, a shutter operating solenoid carried by said plate, and an armature for said solenoid engaging said shutter to rock the same on its pivot when said solenoid is energized.

In witness whereof, we have hereunto set our hands and seals.

JAMES K. BURLEIGH. [L. S.]
LAUREN V. WHITE. [L. S.]

It is hereby certified that the name of the assignee in Letters Patent No. 1,213,456, granted January 23, 1917, upon the application of James K. Burleigh and Lauren V. White, of Kalamazoo, Michigan, for an improvement in "Signaling Devices for Automobiles," was erroneously written and printed as "Arthur L. Zwister," whereas said name should have been written and printed as *Arthur L. Zwister*; page 2, line 125, of the printed specification, for the word "gounded" read *grounded*; and that the said Letters Patent should be read with these corrections therein that the same may conform to the record of the case in the Patent Office.

Signed and sealed this 13th day of February, A. D., 1917.

[SEAL.]

R. F. WHITEHEAD,

Acting Commissioner of Patents.

Cl. 40—52.
